UNITED STATES PATENT OFFICE.

FRANK L. ROSE, OF HELENA, MONTANA.

POTATO-ASSORTER.

1,085,162.

Specification of Letters Patent. Patented Jan. 27, 1914.

Application filed April 15, 1913. Serial No. 761,225.

To all whom it may concern:

Be it known that I, FRANK L. ROSE, a citizen of the United States, residing at Helena, in the county of Lewis and Clark 5 and State of Montana, have invented certain new and useful Improvements in Potato-Assorters; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this 10 specification.

This invention relates to new and useful improvements in potato picking and assorting apparatus and comprises a simple and efficient device of this nature having various 15 details of construction and combinations and arrangements of parts which will be hereinafter fully described, shown in the accompanying drawings and then specifically defined in the appended claims.

25 I illustrate my invention in the accompanying drawings, in which:—

Figure 1 is a side elevation of my invention. Fig. 2 is a top plan view. Fig. 3 is a cross sectional view. Fig. 4 is a top plan view of an assorting table. Fig. 5 is a sectional view on line 5—5 of Fig. 4, and Fig. 6 is a detail sectional view on line 6—6 of Fig. 1.

Reference now being had to the details of 35 the drawings by numeral, 1 designates the frame of the apparatus having the forward axles 2 and rear axles 3. Rising from said frame are the standards 4 which support the beams 5 upon which a shaft 6 is journaled in suitable bearings and upon which shaft are mounted the two sprocket wheels 7, shown clearly in Fig. 2 of the drawings.

A conveyer frame, designated by numeral 45 8, carries at its lower end a shaft 9, having bearings in the adjustable bearing block 10 against which an adjusting screw 11 is adapted to bear. Fixed to the shaft 9 are the sprocket wheels 12 and about the sprocket wheels upon the two shafts 6 and 50 9 the endless conveyer chain 13 travels, which chain has at intervals the laterally projecting fingers 14, shown clearly in Fig. 6 of the drawings, and which project at right angles from the length of the chain.

55 It will be noted that each of said fingers 14

has its upper end bent to form an outwardly extending hook 15 and upon the outer face of each finger is a shoulder 16.

Cross chains, designated by numeral 17, are adapted to engage fingers upon opposite 60 sides of the conveyer chain and the end link of each chain 17 is adapted to have a sliding movement limited by said hooks 15 and the shoulders 16.

The conveyer frame 8 is pivoted at its 65 rear end upon the shaft 6 and its forward lower end is adjustable, being connected by means of cables 18 with the shaft 19 about which they wind, said shaft 19 being journaled in bearings upon the frame 1. A 70 worm wheel 20 is fixed to one end of the shaft 19 and is in mesh with a worm 21 upon the vertical shaft 22 to the upper end of which the wheel 23 is fastened and which latter is provided with a handle 24, forming 75 convenient means for the operator, sitting upon the seat 25, to raise or lower the forward end of the conveyer frame. Said conveyer frame 8 has a trough-shaped bottom, designated by numeral 26, the forward end 80 of which serves as a scoop and into which the potatoes are pushed by the series of chains 17.

A sprocket wheel 27 is fixed to the shaft 6 and passes about a sprocket wheel 28, shown 85 in Fig. 1 of the drawings, and which is fastened to the axle 3 and affords means for driving the conveyer chains.

Upon reference to Fig. 2 of the drawings, it will be noted that the bottom of the conveyer frame is provided with elongated slots 29 through which dirt is allowed to fall as the potatoes are being raised up by the conveyer chain. The upper end of the trough forming the bottom of the conveyer frame is designated by numeral 30 and is 90 downwardly curved as shown in Fig. 1 and extends over the edge of the assorting table 31, details of which latter are shown in Figs. 4 and 5. The assorting table 31 is 100 provided with pivotal lugs 32 projecting from the opposite edges thereof near its front end which lugs have pivotally connected thereto the links 33 which in turn, at their upper ends, are pivotally mounted 105 upon the pins 35 supported by the beams 5.

A bag-holding platform, designated by numeral 36, is fastened to the rear end of the truck upon which the bag 37 to receive the potatoes is held with the downwardly 110

projecting exit end 38 of the assorting table extending to a location above the bag where the potatoes may be guided therein as they are assorted.

5 Fixed to a shaft 40 which is journaled in bearings 41 upon the opposite beams 5 are the cams 46 and about each cam is a strap 47 and to each strap a rod 48 is fastened, one end of which is apertured and is pivotally connected to the pins 32 which project from the opposite side of the assorting table. The means for rotating the cams consist of the belt 64 which passes about a pulley 65 upon the shaft 6 and also a pulley 66 upon the shaft 40.

10 Upon reference to Figs. 4 and 5 of the drawings, it will be noted that said assorting table has a rack made up of the strips 49, spaced apart and provided for the purpose of allowing the smaller potatoes to fall therethrough upon the bottom of the table and be directed by the inclined ridges 50 into the exit opening 38, while the larger potatoes, which will not pass intermediate 15 the strips 49, are guided by the inclined ridge 51 into the openings 52. The said table has hooks 53 fastened to the opposite sides thereof and to each hook is fastened a chain 54 which winds about the shaft 55 20 which is journaled in bearings 56 upon the opposite beams 5. A hand wheel 57 is fixed to the shaft 55 and also a ratchet wheel 58 is keyed to the shaft 55. A pawl 59 is pivotally mounted upon a pin 60 and is provided 25 with an arm 61 which is fastened, through the medium of the links 62, with the operating lever 63, said lever 63 being pivotally mounted upon one of the beams 5.

30 The operation of my invention will be readily understood and is as follows: The 40 conveyer frame is adjusted so that the lower scoop end of the frame thereof will scoop up the earth and the potatoes as the apparatus is moved forward, motion being imparted to 45 the conveyer chain by the driving axle of the apparatus. As the several cross chains 17 come in contact with the earth and the potatoes, the latter will be drawn up into the slotted bottom of the conveyer frame, the 50 dirt falling through the longitudinal spaces formed in the bottom thereof. By the provision of the peculiar mounting of the chain 17, it will be noted that the end links have a slight play in the spaces intermediate the 55 hooks 15 and the shoulders 16, thus automatically adjusting themselves to potatoes of different sizes, and thereby avoiding the cutting of the potatoes in the event of the chains coming in contact first with small 60 potatoes and then those of larger sizes.

65 As the potatoes reach the upper end of the conveyer frame, they will fall down the curved bottom which extends over the rear end of the assorting table and falling upon the strips 49, the smaller potatoes will

readily pass through between the strips and, falling upon the bottom of the table, will roll down the incline and through the central opening 38, while the larger potatoes rolling off the ends of the strips will be diverted by 70 the ridges 51 toward the holes 52 through which they are allowed to pass into the bags which are placed beneath for their reception.

75 In order to allow the potatoes to readily assort, a vibratory movement is imparted to the assorting table through the medium of the cam members which are rotated by the belted connection with the driving shaft 6. Through the medium of the hand wheel 57, 80 the free end of the assorting table may be raised or lowered as may be desired and held in adjusted position by means of the ratchet and pawl, while the forward end of the conveyer frame may be raised and lowered by 85 the manipulation of the hand wheel 23.

What I claim to be new is:—

1. An apparatus for picking up and assorting potatoes comprising a truck, a conveyer frame pivotally mounted thereon and 90 having a slotted bottom with a scoop-shaped lower end, an endless conveyer having transverse chains, the end links of which have sliding pivotal connections with projections upon the conveyer and adapted to elevate the potatoes up the inclined bottom of the conveyer frame, and an assorting table upon which the potatoes are delivered from the conveyer, as set forth.

2. An apparatus for picking up and 100 assorting potatoes comprising a truck, a conveyer frame pivotally mounted thereon and having a slotted bottom with a scoop-shaped lower end, an endless conveyer having transverse chains, the end links of which have 105 sliding pivotal connections with projections upon the conveyer and adapted to elevate the potatoes up the inclined bottom of the conveyer frame, an assorting table upon which the potatoes are delivered from the 110 conveyer, and means for adjusting said conveyer frame, as set forth.

3. An apparatus for picking up and assorting potatoes comprising a truck, a conveyer frame pivotally mounted thereon and 115 having a slotted bottom with a scoop-shaped lower end, and endless conveyer having transverse chains, the end links of which have sliding pivotal connections with projections upon the conveyer and adapted 120 to elevate the potatoes up the inclined bottom of the conveyer frame, an assorting table upon which the potatoes are delivered from the conveyer, a winding shaft upon the truck, means for rotating said shaft, and 125 cable connections between the winding shaft and lower end of the conveyer frame, as set forth.

4. An apparatus for picking up and assorting potatoes comprising a truck, a con- 130

veyer frame pivotally mounted thereon and having a slotted bottom with a scoop-shaped lower end, an endless conveyer mounted upon said frame, laterally projecting fingers upon said conveyer terminating in outwardly curved ends, a shoulder upon the outer face of each finger, cross chains, the end links of which engage said fingers and are limited in their movements by said

curved ends and shoulders, and means for driving the conveyer, as set forth.

In testimony whereof I hereunto affix my signature in presence of two witnesses.
